United States Patent Office.

F. W. DEAN, OF TREMONT, ILLINOIS.

Letters Patent No. 90,430, dated May 25, 1869.

IMPROVED HARNESS-BUCKLE.

The Schedule referred to in these Letters Patent and making part of the same

To all whom it may concern:

Be it known that I, F. W. DEAN, of Tremont, in the county of Tazewell, and State of Illinois, have invented a new and improved Harness-Buckle; and I do hereby declare that the following is a full, clear, and exact description thereof, which will enable those skilled in the art to make and use the same, reference being had to the accompanying drawings, forming part of this specification, in which—

Figure 1 is a top view of my invention.

Figure 2 is a section of the same through the line $x\ x$, fig. 1.

Similar letters of reference indicate corresponding parts.

The object of this invention is to provide an improved buckle for traces and other parts of harness to which it may be applicable.

It consists of a metallic loop, having a hinged or pivoted tongue, located in a recess formed in the top plate of the said metal loop, and which permits the entering trace to pass under it, but catches in the first hole that presents as the trace is retracted or drawn in the reverse direction.

In the drawing, the hames-trace, to which the metallic loop is riveted, is lettered A.

The loop B is affixed to this trace by rivets $a\ a$, or other suitable means.

The upper plate of the loop B is swaged, cast, or otherwise formed with a recess, b , within which a curved tongue, d , is pivoted, in such a position that its point

will readily slip into the holes of the trace-strap C as the latter is drawn toward the said point.

When the trace-strap is pushed from the point of the tongue, as is the case when the said strap is to be taken up or shortened, the point of the tongue slips over the holes without catching, as shown by the red outline, but when retracted in, or drawn back in the reverse direction, the point of the tongue will catch in the first hole c , which it encounters, and as the strap is further retracted, the tongue will be brought to assume a more vertical position by passing through the hole c , and catching in the slot e in the bottom plate of the loop, whereby a firm point of resistance to the draught-strain brought upon the trace-strap C is obtained.

D D D are the ordinary leather loops, sewed to the hames-trace.

I claim as new, and desire to secure by Letters Patent—

The harness-buckle, consisting of the metallic loop B, provided with the semicircular case b , formed centrally upon its side, to receive and enclose the curved pivoted tongue d , whose free end engages with the edge of the slot e , formed in the lower plate of the loop, all constructed as herein described for the purpose specified.

F. W. DEAN.
